UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,817, dated October 29, 1895.

Application filed September 27, 1895. Serial No. 563,931. Term of patent 3½ years.

To all whom it may concern:

Be it known that I, CHARLES BOOZ, a citizen of the United States, residing at Buffalo, in the county of Erie and State of New York, 5 have invented and produced a new and original Design for Wall-Paper, of which the following is a specification, reference being had to the accompanying drawing, showing a part thereof.

10 The design consists of a series of oval figures or panels with open wreaths of leaves surrounding the bottom and sides of said figures or panels and Colonial style of ornaments in the center of said panels, as represented in the accompanying drawing. The 15 figures or panels are placed at regular distances apart over the surface of the paper.

The border of the design also consists of oval figures or panels with Colonial style of

ornaments in the center and open interlacing 20 wreaths of leaves extending from the bottom of said panels upwardly on each side thereof. Light ornamental scrolls are arranged below the open wreaths of leaves and are connected by small upright ornaments, as shown in the 25 drawing.

What I claim is—

1. The design for wall paper herein shown and described.
2. In the design for wall paper, the border 30 herein shown and described.

Witness my hand this 24th day of September, 1895.

CHARLES BOOZ.
